UNITED STATES PATENT OFFICE.

WILLIAM J. FAUL, OF NEW YORK, N. Y.

LUBRICATING DEVICE.

SPECIFICATION forming part of Letters Patent No. 309,613, dated December 23, 1884.

Application filed July 15, 1884. (No model.)

To all whom it may concern:

Be it known that I, WILLIAM J. FAUL, a citizen of the United States, and a resident of the city and county of New York, in the State 5 of New York, have invented a new and useful Improvement in Lubricating Devices, of which the following is a specification, reference being had to the accompanying drawings.

My invention relates to that class of lubricating devices in which grease or other lubricating material solid at ordinary atmospheric temperatures, but easily liquefied by friction, is used in the form of a stick or cartridge, and, being fed against a journal, liquefies sufficiently for lubrication, as required.

The invention consists in a lubricating-cartridge composed of two lubricating materials or compounds of different degrees of hardness, the harder material or compound serving as a 20 support to sustain the softer material or compound.

The invention also consists in the combination, in the form of a cartridge, of a shell or body of solid grease or lubricating substance 25 or compound, and an internal core of harder material which, while it stiffens said shell or body, is capable of reduction therewith.

The invention also consists in the combination, as hereinafter described, of a stick or 30 plug of solid lubricating material, a core of harder material, and a weight employed to press the grease toward the surface to be lubricated.

Figure 1 is a longitudinal sectional view illustrating one form of a lubricating-cartridge constructed according to my invention. Fig. 2 is a transverse section of the same. Figs. 3, 4, 5, 6, and 7 are transverse sectional views of various modifications of the same. Fig. 8 is 40 a side view, partly in section, of another form of lubricating-cartridge constructed according to my invention. Fig. 9 is a transverse sectional view of the same.

Similar letters of reference denote corresponding parts in all the figures.

The core or harder material is denoted by A in the several figures. B indicates the body of grease or other softer but yet solid lubricating material, and D designates a weight of 50 metal or other heavy material attached to the cartridge to keep it to its place. The harder

part A, which in Figs. 1, 2, 3, 4, 5, 6, and 7 is illustrated as a core, may be composed of any material which, while it is hard and stiff enough to support the body of grease that it 55 may not be easily broken, is of such a nature that it will be reduced and consumed with the body B in lubrication. This may be accomplished by molding said core of a harder and stronger lubricating compound than that used 60 in the body of grease—as, for example, a compound of tallow, sulphur, and plumbago, which, by varying the quantities of its component parts, may be made of any desired hardness. There are many other lubricating 65 compounds which may be used for the same purpose. In molding or constructing said core it is made a little longer than the body of grease, so that it will project a little at one end, as illustrated at i of Fig. 1, for the purpose of attaching it and the body of grease 70 which surrounds it to the weight D by inserting the said projecting end i tightly into a hole provided for it in the said weight. It may be made of any form—for example, solid 75 and cylindrical, as illustrated in Figs. 1 and 2, or solid and fluted, as illustrated in section in Fig. 3, or hollow and cylindrical, as illustrated in section in Fig. 4. Or this core may be constructed of material in sheets, in which 80 case it may be made of any convenient form—as, for example, with three radial wings or four radial wings, as illustrated in Figs. 5, 6, and 7. Around this core is molded the shell or body of grease B, which may be of any convenient size and form. In the examples given 85 it is illustrated as being cylindrical, that form seeming preferable. This body of grease should in all cases be composed of such material that, while it is solid at ordinary atmospheric temperatures, it will be easily liquefied 90 by friction.

Instead of harder lubricating material, which sustains, stiffens, and strengthens, the cartridge, being a core, it may be reversed, and 95 the softer part may be the core and the harder part the shell, as is illustrated in Figs. 8 and 9. In this case the outside shell or case of harder material is first molded and afterward filled with the softer lubricant. This form of the 100 cartridge may be of any convenient shape. In the example given it is represented as be-

ing cylindrical, that form seeming preferable. This grease cartridge is used as lubricating devices of its class commonly are, and may be applied to any journal having space enough 5 to admit its free motion lengthwise in the oil-hole.

What I claim, and desire to secure by Letters Patent, is—

1. A lubricating-cartridge composed of two 10 lubricating materials or compounds of different degrees of hardness, the harder material or compound serving as a support to sustain the softer material or compound, substantially as herein described.

15 2. A lubricating cartridge or stick com-

posed of a shell or body of solid grease or lubricating material, and an internal core which, while it stiffens said shell or body, is capable of reduction therewith, substantially as and for the purpose herein described.

3. In a lubricating grease cartridge, the combination, with the body of grease and a weight, of an internal core, one end of which enters into said weight for the attachment of 25 the body of grease thereto, substantially as and for the purpose herein described.

WM. J. FAUL.
